TOILET SEAT

John Corser, Minneapolis, Minn.

Application December 13, 1937, Serial No. 179,507

1 Claim. (Cl. 4—237)

My invention relates to toilet seats.

One object of my invention is to provide a seat for mounting on a toilet bowl that shall be simple in form and construction and that shall have a dense hard fluid-resisting unbroken outer covering.

Another object of my invention is to provide a toilet seat having a pair of spaced seat pads and a connecting member, the entire outer surface of the pads and of the connecting member being continuous and substantially unbroken.

Another object of my invention is to provide a toilet seat for mounting on a toilet bowl, comprising a pair of seat pads and a connecting member of generally open oval shape, at the ends of which the seat pads are located, the three elements of the structure being integral with each other.

Another object of my invention is to provide a unitary toilet seat comprising a pair of seat pads and a connecting member of open oval shape, the seat pads being positioned at the ends of the side portions of the connecting member and forward of the center of a toilet bowl, the connecting member being so shaped as to make it unusable as a means for supporting a user of a toilet bowl.

Other objects of my invention will either be apparent from a description of several forms of toilet seats embodying my invention or will be set forth in the appended claim.

In the drawings,

Figure 1 is a fragmentary top plan view of a toilet seat embodying my invention and shown as being mounted on a toilet bowl.

Fig. 2 is a view in lateral section therethrough, taken on the line 2—2 of Fig. 1.

Fig. 3 is a view in lateral section therethrough, taken on the line 3—3 of Fig. 1.

Fig. 4 is a top plan view, similar to Fig. 1 but showing a modified form of device embodying my invention.

Fig. 5 is a view in lateral section therethrough, taken on the line 5—5 of Fig. 4.

Fig. 6 is a view in lateral section therethrough, taken on the line 6—6 of Fig. 4.

Fig. 7 is a view in lateral section, similar to Fig. 6 but showing a modified form of construction.

Fig. 8 is a view in side elevation, of both the devices shown in Figs. 1 and 4, the top portion of a toilet bowl being also shown.

Fig. 9 is a top plan view of still another modification embodying my invention, shown as mounted on a toilet bowl.

Fig. 10 is a view in side elevation of the parts shown in Fig. 9, a part only of a toilet bowl being shown.

Fig. 11 is a view in lateral section therethrough, taken on the line 11—11 of Fig. 9, and,

Fig. 12 is a view in lateral section therethrough on the line 12—12 of Fig. 9.

Referring first to Fig. 1 of the drawings, a unitary toilet seat includes a connecting member 21, of generally open oval shape and a pair of seat pads or portions 22, only one of which is shown. The connecting member may best be described as an incomplete oval and the side portions thereof may each be bent or shaped so that the distance between these side portions is greater than is the distance between the side portions of the usual open front end toilet seat now in common use. 10 The seat pads 23 are relatively short and more or less rectangular in outline or contour, the top surface being preferably but not necessarily raised above the top surface of the connecting member to clearly and sharply define the seat portion of the structure and to set it apart from the connecting member.

I may make the structure comprising the two spaced seat pads and the connecting member of wood, either of one piece or of a plurality of layers 20 glued or otherwise fastened together, to provide a relatively light weight but strong device.

A rearwardly projecting extension 25 is integral with the connecting member 21 and may be provided with an opening 27 at each side for receiving a hinge pin 29 which is part of a pillar hinge 31. While I have shown a specific form of hinge structure, I do not wish to be limited thereto as any suitable hinge means may be used.

The entire outer surface of the seat structure 30 including the seat pads 23, the connecting member 21 and the extension 25 are covered with a non-porous, hard, dense and closely-adhering unbroken fluid-resistant covering 32. As an example of such coatings I may mention enamel or 35 molded or formed composition material. As an example of a formed material I may use cellulose nitrate or cellulose acetate or other similar materials, I prefer to make the coating of such material as to have a highly polished outer surface so that the tendency of extraneous solid and fluid material to adhere to the seat will be reduced to as great a degree as possible.

Referring now to Figs. 4 to 6 inclusive I have there shown a reinforced seat structure comprising a pair of seat pads 33 and a connecting member 35, both of these parts having substantially the same shape and contour as was described in connection with Fig. 1.

Fig. 5 shows a cross-sectional view of the connecting member and it will be noted that I provide a metal reinforcing member 37, of substantially inverted channel shape in lateral section and an enclosing flat metal plate 39 located in the open end of member 37. A filler 41, which 50 may be of wood, is positioned in the member 37 and is of such shape and dimensions as to substantially fill the space within the reinforcing member. The adjacent edges of the metal members may be secured together as by spot welding 55 60

or by a seam of welding metal or by any other suitable means with the object of combining light weight with relatively great strength. I may use any desired structural shape of reinforcing member having relatively great strength and relatively light weight and a filler, the weight of which per unit of volume is less than that of the reinforcing member.

Referring to Fig. 6 I have there shown how 10 the shape of member 37 may be changed at those portions thereof which are in the seat pads. The wood filler 43 is of course changed to conform to the altered shape of the reinforcing member 37, providing at the same time a somewhat greater width. Substantially the same 15 method of changing the shape of the reinforcing member at the rear extension 45, as was used in the seat pads, may be employed.

Fig. 7 shows a view similar to that of Fig. 5 20 except that the reinforcing member 47 is of substantially angle bar shape and the wood filler 49 is complementary thereto as shown.

The entire seat structure including the seat pads, the connecting member and its rearward 25 extension are covered with a closely adhering, non-porous, hard and substantially unbroken covering 51, over its entire outer surface. This covering may as has already been hereinbefore described, be a suitable enamel or it may be a 30 molded or formed composition material with a highly polished outer surface.

Referring to Fig. 8, I have there shown my improved toilet seat mounted on a toilet bowl 53 and I wish to point out that I locate the lower 35 surface of the seat an appreciable distance above the top edge of a toilet bowl to reduce the tendency of foreign matter to collect therebetween. To this end the pillar hinges are made relatively high and a depending support 55 is 40 secured to each seat pad at its under side. These supports are preferably so made and so secured to the seat pads as to provide a tight joint therebetween to reduce the tendency of foreign matter to lodge thereon.

Referring to Figs. 9 to 12 inclusive, I have 45 there illustrated a still further modification of device embodying my invention. A metal reinforcing member 57, of substantially circular cross section, extends from one of the two seat pads 59 through the connecting member 61 to the other seat pad 59. In the respective seat pads the reinforcing member may be returnbent on itself as shown in Fig. 9 of the drawings to provide the somewhat greater width for the 50 seat pads. As shown in Fig. 10, the reinforcing member 57 is bent upwardly where the connecting member joins with or merges into the seat pads so that the top surface of the seat pads will be positioned an appreciable distance 55 above the connecting member. The reinforcing member 57 is covered with dense, hard, non-porous, moisture-resisting covering 63 adhering closely to the reinforcing member and in this form of the device I prefer to use a suitable or formed composition material, the covering being made relatively thick. Any desired shape of the material in cross-section may be used.

Each seat pad may have depending therefrom a spacer or support 65, which may be integral 60 with the material 63 of the seat pads and a resilient bumper 67 may be secured against the bottom surface of each spacer in any suitable or desired manner.

I have shown one form of cross section of the connecting member 61 in Fig. 11 and one form of cross section of the seat pads in Fig. 12. These forms are representative only and are not to be considered as limiting. In this form of 5 seat structure also the entire outer surface is highly polished and substantially unbroken over the entire seat structure.

It may be here pointed out that the seat structures embodying my invention each comprise 10 two seat pads and a connecting member unitary or integral with each other, the seat pads being so shaped and positioned as to force a user of a toilet bowl equipped with one of my toilet seats to support his weight on the seat 15 pads alone. The shapes of the seat pads and of the connecting member are quite different from each other so that it is easily to be seen that the connecting portion is not to be used as a user-supporting means. The connecting portion 20 is also shaped differently from the open front toilet seats now in use in that the sides thereof are spaced apart much more than is the case for the corresponding sides of the open front seats. At the same time the outside surface 25 is substantially smooth and unbroken, providing a pleasing appearance and making it easy to thoroughly clean the seat. The ease of cleaning the seat is increased by the covering used, which covering has a highly polished outer surface, which is moisture repellent to a high 30 degree and which will also withstand the rough usage to which it may be subjected.

The seat pads are preferably made of such 35 contour and have such a profile that it is easy for a user to place a small piece of sanitary sterilized paper or other material on each seat pad before use of the seat, without appreciable danger of tearing the piece of protective material by the user's weight. The relatively small pieces 40 of protective material which can be used make it possible to make economical use of such sheets.

I have shown the seat pads as being positioned 45 relatively far towards the front end of a toilet bowl, but I may locate them in any suitable position longitudinally of a toilet bowl.

While I have shown outer coverings of substantial thickness, it is to be understood that I may vary the thickness of the coatings as may be found necessary or desirable to meet operating 50 conditions. As has been stated I may make use of any one of a number of materials now on the market for the outer covering, the required characteristics of this material having already been set forth.

While I have shown and described several 55 forms of devices embodying my invention, which forms appear to best embody the invention, I do not desire to be limited thereto and the appended claim is to be limited only by the prior art.

I claim as my invention:

A unitary toilet seat for removable mounting 60 on a toilet bowl and comprising a pair of separate seat pads and a connecting member of open oval shape, the longitudinal portions of the connecting member being so shaped as to extend laterally beyond the inside surface of the side walls of a toilet bowl to substantially preclude engagement therewith by a user of the seat.

JOHN CORSER. 70
